GLASS DRAWING APPARATUS

Howard L. Halbach, Clarksburg, W. Va., assignor to Pittsburgh Plate Glass Company, Allegheny County, Pa., a corporation of Pennsylvania

Application February 13, 1937, Serial No. 125,609

2 Claims. (Cl. 49—17)

The invention relates to apparatus for drawing sheet glass, and particularly to the water coolers which are employed above the glass bath to insure more rapid cooling of the surface of the bath and the base of the sheet, and thus permit more rapid drawing. The coolers most commonly employed are merely metal boxes of approximately rectangular cross section having connections whereby water may be continuously circulated through the devices. Coolers of this type are subject of excessive sweating and warpage. The condensation which forms on the exterior of the boxes drips onto the surface of the glass tending to stain it, and the warpage under heat augmented by the weight of the boxes, tends to distort them, so that their central portions are closer to the bath than their ends, thus tending to make the sheet which is drawn thicker at the middle than at the ends. The objects of the present invention are to provide coolers in which less sediment collects and on which the formation of condensation is reduced to a minimum; which are more resistant to warping; which in service have their bottom faces substantially parallel to the surface of the bath throughout the length of the coolers; and which give a uniform cooling effect upon the bath and the glass sheet from one side of the bath and the sheet to the other side thereof. One embodiment of the invention is illustrated in the accompanying drawings, wherein:

Figure 1 is a vertical section through a tank and drawing apparatus involving an improvement. Fig. 2 is a longitudinal section through the cooler. Fig. 3 is a side elevation of the cooler. And Fig. 4 is a section through the cooler on the line IV—IV of Fig. 2.

Referring to the general arrangement of the parts as shown in Fig. 1, 5 is a forehearth or drawing kiln connected at its left hand end with a melting tank 6. Lying above the surface of the bath in the kiln 5 is a roof or cover consisting of the plates 7, 7 and the L blocks 8, 8. The bath is provided with the usual skim bar 9 and the sheet 10 is drawn upward continuously through a roller leer 11 of the Fourcault type. The coolers 12, 12 are located above the surface of the bath adjacent the line of draw and are shown in detail in Figs. 2, 3, and 4.

The particular cooler shown is made up of five metal pipes 13, 14, 15, 16, and 17 arranged one above the other in series, and of substantially rectangular cross section, as indicated in Fig. 4. These pipes are preferably of drawn steel tubing and are secured rigidly together by spot welding

at intervals along the tubes, as indicated at 18. The bottom tube 17 is slightly bent, as indicated in Fig. 2, so that its central portion is at a somewhat higher level than the ends. The proper curvature is secured by the use of the spacing strips 19, 20, 22, and 23, whose upper and lower surfaces are welded to the tubes 16 and 17.

An inlet pipe 24 is provided at one end of the cooler and an outlet pipe 25 at the other end, water being supplied under pressure so that a cooling circulation is secured. In practice, the pipes 24 and 25 form the means of support for the cooler, such pipes being supported from above by means of hooks or other suitable connections. The pipe 24 leads into a vertical pipe 15 welded to the ends of the pipes 13 to 17 and communicating at its lower end with the right hand end of the bottom pipe 17. Communications are provided between the left hand ends of the pipes 17 and 16, and between the pipes 15 and 14. At the right hand end of the pipes communications are provided between the pipes 16 and 15 and between the pipes 14 and 13. By virtue of these connections, the water which is admitted to the right hand end of the pipe 17 flows back and forth through the pipes and finally discharges from the left hand end of the pipe 13, the flow through the various pipes being indicated by the arrows.

The communications between the ends of adjacent pipes are provided by beveling the ends, as indicated at 27 and 28 of Fig. 2 and then closing the openings by means of a cap comprising the end plate 29 and two triangular side plates 30, which fit the beveled tube ends. These caps are secured in position by welding.

The structure as thus provided is relatively strong and rigid, so that when supported from the pipes 24 and 25, as heretofore pointed out, there is practically no sagging intermediate the ends of the coolers. Due to the heat of the glass there is a tendency of the bottom tube 17 to expand and carry the central portion of the cooler toward the bath. This tendency is compensated for by the arching of the tube 17 as heretofore explained. In a cooler of 90 inches in length, the amount of arching is preferably about $\frac{3}{8}$ ths of an inch, although this may vary somewhat depending upon conditions. Due to the back and forth circulation through the cooler, the cooling effect of the water is made relatively uniform from one end to the other and the temperature of the discharge water is ordinarily very considerably higher than with box coolers as heretofore used. Due to this fact, the condensation formed

upon the exterior of the cooler is substantially less than with the type of coolers heretofore referred to, so that the amount of drip from the cooler to the surface of the glass bath is reduced to a minimum. As a result, any discoloration of the surface glass incident to the drip is minimized. The collection of sediment is also less in a cooler of this type than in a box cooler due to the greater velocity of flow which keeps the interior of the pipes relatively clear from deposit. Other advantages incident to the construction will be readily apparent to those skilled in the art.

It will be understood that the particular structure shown and described is subject to modification in matters of detail without involving a departure from the invention as defined in the claims. For example, the arching of the bottom tube may be modified in degree depending on conditions to be met. In some cases, the bottom tube will be curved to such an extent that in service it is still slightly further from the bath at its control portion than at its ends, so as to give more cooling effect on the bath at the center than at the sides. The points of inlet and discharge may be modified as to location within certain limits without materially affecting the functioning of the device, and the details of construction as to the closures of the tubes, while advantageous, may also be modified without departing from the invention.

What I claim is:

1. In combination in glass drawing apparatus, means for drawing a sheet of glass from a bath, and a cooler above the glass bath adjacent the line of draw of the sheet comprising a series of metal pipes of rectangular cross section one above the other and rigidly secured together along their lengths, communications between each adjacent pair of pipes at one end thereof so that a continuous back and forth passage through all the pipes is provided, and an inlet and an outlet for the cooler, one of which is connected to one end of the top pipe of the series and the other of which is connected to one end of the bottom pipe of the series. 10

2. In combination in glass drawing apparatus, means for drawing a sheet of glass from a bath, and a cooler above the glass bath adjacent the line of draw of the sheet comprising a series of metal pipes of rectangular cross section one above the other and rigidly secured together along their lengths, communications between each adjacent pair of pipes at one end thereof so that a continuous back and forth passage through all the pipes is provided, an inlet connected to one 20 end of the bottom pipe of the series and an outlet connected to one end of the top pipe of the series, the bottom pipe of the series being bent so that its central portion lies at a higher level than its ends. 25

HOWARD L. HALBACH. 30
